CLAIM

The ornamental design for the snowmobile headlight, as shown and described.

DESCRIPTION

FIG. 1 is front-elevational view of a snowmobile headlight, showing our new design;

FIG. 2 is a rear view of the snowmobile headlight;

FIG. 3 is an enlarged left side-elevational view of the snowmobile headlight;

FIG. 4 is an enlarged right side-elevational view of the snowmobile headlight;

FIG. 5 is a top view of the snowmobile headlight; and,

FIG. 6 is a bottom view of the snowmobile headlight.

The broken lines are included for the purpose of illustrating portions of the article and form no part of the claimed design.

1 Claim, 6 Drawing Sheets(56)
